POWER-DRIVEN CAN OPENER

Dominic J. De Fano, River Grove, Ill., assignor to McGraw-Edison Company, Milwaukee, Wis., a corporation of Delaware

Filed Jan. 25, 1960, Ser. No. 59,151

Term of patent 14 years

(Cl. D22—2)

Fig. 1 is a front perspective view of a power-driven can opener embodying my new design, the back thereof having a planar surface that is unornamented;

Fig. 2 is a side elevational view thereof, the side opposite thereto being substantially identical in appearance; and Fig. 3 is a bottom plan view thereof.

I claim:

The ornamental design for a power-driven can opener, as shown and described.
